(57) **CLAIM**

I claim the ornamental design for a bilateral stimulator with case, as shown and described.

DESCRIPTION

FIG. 1 is a perspective view of a bilateral stimulator with case showing a single bilateral stimulator separately for ease of illustration;

FIG. 2 is a front elevation view thereof;

FIG. 3 is a right side elevation view thereof;

FIG. 4 is a left side elevation view thereof;

FIG. 5 is a top plan view thereof;

FIG. 6 is a rear elevation view thereof;

FIG. 7 is a bottom plan view thereof;

FIG. 8 is a perspective view of a bilateral stimulator with case in an open configuration;

FIG. 9 is a perspective view of a bilateral stimulator with case shown separately for ease of illustration;

FIG. 10 is a front elevation view thereof;

FIG. 11 is a left side elevation view thereof;

FIG. 12 is a right side elevation view thereof;

FIG. 13 is a top plan view thereof;

FIG. 14 is a rear elevation view thereof; and,

FIG. 15 is a bottom plan view thereof.

The broken lines shown in the design of the bilateral stimulator with case in FIGS. 1-15 form no part of the claimed design.
